(57) CLAIM

The ornamental design for a tape dispenser, as shown and described.

DESCRIPTION

FIG. 1 is a perspective view of the tape dispenser according to the present invention.

FIG. 2 is a side view of the tape dispenser illustrated in FIG. 1.

FIG. 3 is a top view of the tape dispenser illustrated in FIG. 1.

FIG. 4 is a front view of the tape dispenser illustrated in FIG. 1.

FIG. 5 is a bottom view of the tape dispenser illustrated in FIG. 1; and,

FIG. 6 is a back view of the tape dispenser illustrated in FIG. 1.

The structure depicted by means of broken lines in the figures has been shown for illustrative purposes only and forms no part of the claimed design.
